(57) **CLAIM**

The ornamental design for a roofing support system, as shown and described.

DESCRIPTION

FIG. 1 is a perspective view of a selectively attachable/detachable roofing support system comprising an upper core member of a substantially rigid molded polymer comprising integral right side and left side pockets comprising handles or grips and a lower core member or base comprising a substantially rigid molded polymer and an attached lower cover layer member comprising an elastomeric polymer foam, in an attached condition;
FIG. 2 is a top view thereof;
FIG. 3 is a bottom view thereof;
FIG. 4 is a left side view thereof;
FIG. 5 is a right side rear view thereof;
FIG. 6 is a front view thereof; and,
FIG. 7 is a rear view thereof.

1 Claim, 5 Drawing Sheets
